UNITED STATES PATENT OFFICE.

ROBERT E. MORRELL, OF WABASH, INDIANA, ASSIGNOR TO WABASH CABINET COMPANY, OF WABASH, INDIANA, A CORPORATION OF INDIANA.

INDEX HOLDER OR TAB FOR FILING-CASES AND THE LIKE.

1,071,625.

Specification of Letters Patent. Patented Aug. 26, 1913.

Application filed November 19, 1909. Serial No. 528,876.

To all whom it may concern:

Be it known that I, ROBERT E. MORRELL, a citizen of the United States, residing at Wabash, in the county of Wabash and State 5 of Indiana, have invented certain new and useful Improvements in Index Holders or Tabs for Filing-Cases and the Like, of which the following is a specification.

This invention relates to improvements in 10 transparent holders for receiving and removably holding an indication card or slip, and the primary object of the invention is to provide an improved device of this character particularly adapted for use in filing 15 cases or cabinets and which holders are fastened to the division leaves or partitions to hold the indication card or slip in such a position as to be readily seen when the case or cabinet is opened for use.

20 A further object is to provide an improved holder of this character which is provided with guides for directing the card or slip into the holder.

A further object is to provide an improved 25 holder of this character constructed of a single piece of transparent material bent upon itself to form a holder having a closed top and which is secured to the division leaf or partition to hold the card or slip projected beyond the edge of the leaf or partition and with the closed top of the holder in a position to receive the greater part of the handling.

A further object is to provide improved 35 means for reinforcing the holder.

A still further object is to provide an improved device of this character which will be simple, durable and cheap in construction and effective and efficient in operation.

40 To the attainment of these ends and the accomplishment of other new and useful objects as will appear, the invention consists in the features of novelty, the construction, combination and arrangement of the several 45 parts hereinafter more fully described and claimed and shown in the accompanying drawings illustrating an embodiment of the invention, and in which—

Figure 1 is an elevation showing a division leaf or partition having an improved device constructed in accordance with the principles of this invention applied thereto; Fig. 2 is a sectional view on line 2—2 of Fig. 1; Fig. 3 is a detail perspective view of 55 one edge of the partition or division leaf

showing a portion thereof projecting beyond the edge of the partition; Fig. 4 is a detail perspective view of the holder removed.

Referring to the drawings and in the present exemplification of the invention, the 60 holder is shown as being applied to a dividing partition or leaf particularly adapted for use in filing cabinets, but it is to be understood that this improved indication card holder or tab may be readily employed in 65 any other form of filing case and may as readily be applied to a sheet or leaf of a book.

In the drawings the numeral 10 designates the division partition or member which 70 is provided with the usual aperture 11 preferably located adjacent its bottom and between the ends thereof, through which aperture the fastening or securing rod common in devices of this character is adapted to 75 pass. The member 10 in the present exemplification of the invention is provided with a tab or ear 12, which projects beyond the upper edge thereof and may be of any desired size and configuration.

The holder, designated generally by the reference numeral 13, is constructed of a sheet of any suitable flexible transparent material and is adapted to be bent upon itself, as shown in Fig. 4, to form a casing, 85 the bend 14 in the material constituting the top of the casing. The material thus bent is placed upon the upper edge of the member 10 so that the projecting ear or tab 12 will extend into the casing 13 so that the 90 bent portion 14 will engage and rest upon the top edge of the ear or tab. The sides 15, 16 of the casing 13 are spaced from each other as shown and are adapted to engage and rest against opposite faces of the 95 member 10 and the holder is secured in position and against removal in any desired or suitable manner, preferably by means of some adhesive material, although the specific manner of fastening the holder constitutes no part of the present invention. One of the sides, preferably the side 16, of the holder is offset, as at 17, to form a 100 casing and guides within the holder for directing a card or slip 18 into the holder and retaining it therein, and the casing and guides thus formed are preferably located intermediate the top and bottom of the holder so that the card or slip will be supported below the upper edge of the ear or 110

tab 12. The ends of the casing formed by the tab 12 and the offset portion 17 of the holder are both preferably open, as shown, to permit the card or slip to be readily inserted or withdrawn from the holder through either end. When the card or slip 18 is in position within the casing it will rest against the face of the ear or projection 12 and is preferably of a length substantially equal to the length of the casing. The holder is secured to the member 10 so that the indication card or slip will be held in a position to be easily seen when the filing case is open, and preferably holds the card or slip projected beyond the edge of the partition or division 10.

With this improved construction it will be apparent that the card or slip 18 will be incased within the holder and will be protected, thereby rendering it possible to provide a sanitary tab and at the same time will keep the card or slip clean. It will also be apparent that by constructing the holder of a single piece of flexible and transparent material, the holder when bent into shape will be continuous and will extend over the edge of the portion to which it is secured so that the closed end formed by the bend 14 will be uppermost, thereby obviating the danger of the parts of the holder becoming separated or split by constant handling. When the holder is secured to the partition or leaf, the body portion thereof is detached from the face of the partition so as to permit the ready insertion or removal of the card or slip.

What is claimed as new is—

1. In a device of the character described the combination of a partition or leaf, a piece of transparent material secured thereto, the body portion of said transparent material being adjacent the face of the partition or leaf and free therefrom, to form a

casing for removably holding a card or slip, and two parallel webs joining the side edges of the free portion of the transparent material with the adjacent portions of transparent material attached to the partition or leaf to form an open-ended guideway for guiding the card or slip into and properly positioning it within the casing.

2. In a device of the character described, the combination of a partition or leaf, a holder constructed of imperforate transparent material secured thereto and adapted to incase and removably hold an indication card or slip, a portion of said holder being spaced from the partition or leaf, said spaced portion being shaped to form spaced guides between which the card or slip is adapted to be inserted, said guides being spaced from the top and bottom of the casing respectively.

3. In a device of the character described, the combination of a partition or leaf, a holder constructed of imperforate transparent material secured thereto and adapted to incase and removably hold an indication card or slip, a portion of said holder being spaced from the partition or leaf and said spaced portion being shaped to form spaced guides between which the card or slip is adapted to be inserted, said guides being spaced from the top and bottom of the casing respectively, the ends of the casing being open to admit of the insertion or removal of the card or slip.

In testimony whereof I have signed my name to this specification, in the presence of two subscribing witnesses, on this 17th day of November A. D. 1909.

R. E. MORRELL.
